FISHING REEL

Morris E. Wood, 128 Compton St., Bronson, Mich.

Filed July 20, 1959, Ser. No. 56,853

Term of patent 14 years

(Cl. D31—4)

Fig. 1

Fig. 2

Fig. 3

FIGURE 1 is a top plan view of a fishing reel showing my new design;

FIGURE 2 is a side elevational view thereof; and

FIGURE 3 is a side elevational view thereof showing the side opposite that shown in FIGURE 2.

The dominant features of my design reside in the full line portions of the drawing.

I claim:

The ornamental design for a fishing reel, as shown and described.
